[Term of patent 7 years.]

To all whom it may concern:

Be it known that I, CHARLES H. LEARNED, of Meriden, in the county of New Haven, Connecticut, have invented a new Design for Funeral Use and Ornament; and I do declare the following, when taken in connection with the accompanying illustration, to be a full, clear, and exact description of the same, and which said drawing constitutes a face view.

This invention relates to a design for an ornamental plate with special reference to funeral use and decoration—that is to say, an ornamental plate which may be attached to a casket, or to flowers, or other parts of funeral decoration, and for analogous purposes; and it consists in the form and outline of an ornamental plate, and in ornamentation, as hereinafter described, and as represented in the accompanying illustration.

The principal feature of the design is a plate of ornamental outline and form, and which forms the base of it, on the surface of which, and represented as covering a part only of the surface, is the representation of a banner surmounted by a crown. At the sides of the banner is represented wheat, and below the banner are represented lily flowers. An appropriate word or words appropriate are placed on the banner.

The crown may be dispensed with, and the ornament consist of the plate of ornamental outline and form, with only the representation of a banner, represented as covering in part only the surface of the plate.

The representation of the banner may be dispensed with, and the ornament consist of the plate of ornamental outline and form, having represented on its surface a crown and wheat, with the word or appropriate words, such as represented in the illustration.

I claim—

1. The herein-described design for funeral ornament and use, consisting of the plate of ornamental outline and form, with the representation on its surface, and represented as covering a part only of the surface, of a banner, as represented in accompanying illustration.

2. The herein-described design for funeral ornament and use, consisting of the plate of ornamental outline and form, with the representation on its surface, and which is represented as covering but a part only of the surface, of a banner surmounted by a crown, as represented in the accompanying illustration.

3. The herein-described design for funeral ornament and use, consisting of the plate of ornamental outline and form, having represented on its surface a crown and wheat, as represented in the accompanying illustration.
